US00D352858S

United States Patent [19]

Farley

[11] **Patent Number:** Des. 352,858[45] **Date of Patent:** ** Nov. 29, 1994[54] **ANATOMICALLY CONFORMABLE SUPPORT PAD**[76] Inventor: **David L. Farley**, 18672 Evergreen Ave., Yorba Linda, Calif. 92686[**] Term: **14 Years**[21] Appl. No.: **8,177**[22] Filed: **May 10, 1993**[52] U.S. Cl. **D6/582; D6/382**
[58] Field of Search ..... **D6/582, 583, 585, 595; 4/596, 581, 582, 583; 5/417, 418, 419, 420, 468, 481, 490, 636, 900.5, 901, 922; 15/215, 216, 217**[56] **References Cited****U.S. PATENT DOCUMENTS**

[57] **CLAIM**

The ornamental design for an anatomically conformable support pad, as shown and described.

DESCRIPTION

FIG. 1 is a front top perspective view of the anatomically conformable support pad of the present invention showing my new design;

FIG. 2 is a front bottom perspective view thereof;

FIG. 3 is a cross-sectional view taken along line 3—3 of FIG. 1;

FIG. 4 is a cross-sectional view taken along line 4—4 of FIG. 1;

FIG. 5 is a cross-sectional view taken along line 5—5 of FIG. 1; and,

FIG. 6 is a cross-sectional view taken along line 6—6 of FIG. 1.
